UNITED STATES PATENT OFFICE.

HARRY S. LEE, OF PLYMOUTH, MICHIGAN.

CORE CENTRALIZER FOR PERMANENT MOLDS.

Application filed January 8, 1925. Serial No. 1,168.

This invention relates to permanent molds, especially molds invented for casting ferrous articles. Molds of this kind expand under relatively great heat, and it is 5 the object of the present invention to provide means which will properly center the core in such a mold.

In the drawings:

Fig. 1 is a vertical section of the mold 10 and the core.

Fig. 2 is a cross section on the line 2—2 of Fig. 1.

Fig. 3 is a plan view of a modified form.

Fig. 4 is a fragmentary vertical section 15 of the same.

Fig. 5 is a detail of one of the pins.

Permanent molds constructed of metal in casting ferrous materials become very hot and expand a few thousandths of an inch; 20 hence the core which is fitted into and held in the mold by the walls of the same will not be accurately centered after the mold becomes heated up. It is, therefore, the 25 object of the present invention to provide a compensating means which will secure accurate casting by properly centering the mold.

In the drawings, I have shown a mold and a core such as would be suitable for casting a piston, but, obviously, other forms of casting could be easily adapted to carry out the invention here described. The mold is made in two sections, *a* and *b*. Either one or the other of these sections can be 30 withdrawn to permit of the insertion of the core *c*. This core has a supporting head in the form of two annular ribs, *d* and *e*, which are fitted on to the seats *h* and *i*, or on the other hand, it may be said that the core 35 head has an annular groove *f* into which fits the internal rib *g* of the mold. It does not matter just how this support is affected; suffice it to say that the upper part of the mold and the core have interlocking 40 projecting and grooved parts, so that after the core has been fitted into one half of the mold the other half of the mold may be put in place, thereby forming a suitable suspension for the core in the mold.

45 However, when the molten metal is poured into the mold it greatly raises the temperature of the mold, and consequently in accordance with a familiar law the mold expands. It thereby draws away from the 50 contacting surfaces of the core. This permits the core to shift slightly in the mold,

and consequently an accurate casting will not result.

I remedy this difficulty by providing in one of the grooves of the mold a plurality 60 of spacing blocks *k* in the form of headed studs which can be turned into tapped holes in the mold sections from the inside of the mold. After once in place they may be adjusted from the outside by loosening up the 65 lock nuts *m* and applying a screw driver to the slotted end *n* of the stud.

It will, therefore, be apparent that as the mold heats up the studs may be released and adjusted to compensate for the expansion 70 of the mold. When the desired adjustment is secured this may be fixed by again tightening the jamb nuts.

This is a most desirable form of adjustment, especially, where the temperature of 75 the mold remains substantially constant during the pouring operations, as it is possible by releasing the lock nuts and adjusting the studs to get a fairly accurate centering of the core and to keep such an adjustment during the entire pouring operations.

In Figs. 3, 4 and 5 I have shown a slight modification of this arrangement wherein 80 tapered pins are used in place of the studs running directly through the side. By this arrangement the adjusting stud is brought 85 on to the top of the mold where it is somewhat easier to operate. Furthermore, it is possible by using a relatively steep taper on 90 the two pins, to reduce the movement of the spacing pin as regards the movement of the adjusting stud so as to get even a finer adjustment than is possible with the stud 95 shown in Figs. 1 and 2.

What I claim is:

1. In a permanent mold, the combination 100 of a plurality of metal mold sections that expand when heated, a core, the core and mold sections provided with inter-engaging surfaces to support the core in the mold, and means for centralizing the core and the mold when the mold sections expand due to the heat.

2. In a permanent mold, the combination 105 of a plurality of expansible metal mold sections, a core, the core and the mold sections provided with inter-engaging surfaces to support the core in the mold, and adjustable means carried by said expansible mold sections which may be given a permanent 110 adjustment to compensate for the expansion

of the mold sections so as to hold the core in a centralized position.

3. In a permanent mold, the combination of a plurality of expansible metal mold sections, a core, the core and the mold sections provided with inter-engaging surfaces for holding the core in the mold, and screw-operated means carried by said expansible metal mold sections for centralizing the core with respect to the mold notwithstanding the expansion of the mold.

4. In a permanent mold, the combination

of a plurality of expansible mold sections, a core, the core and the mold sections provided with inter-engaging portions for suspending the core in the mold in spaced relation with the walls of the mold and permanently adjustable spacing members for properly centralizing the core notwithstanding the expansion of the mold sections. 20

In testimony whereof I have affixed my signature.

HARRY S. LEE.
